UNITED STATES PATENT OFFICE.

JAMES CHRISTY, OF AKRON, OHIO.

DESIGN FOR A WHEEL-TIRE.

43,495.

Specification for Design.

Patented Feb. 4, 1913.

Application filed January 20, 1912. Serial No. 672,498. Term of patent 14 years.

To all whom it may concern:

Be it known that I, JAMES CHRISTY, a citizen of the United States, residing at Akron, county of Summit, and State of Ohio, have invented a new, original, and ornamental Design for a Wheel-Tire, of which the following is a specification, reference being had to the accompanying drawing, forming part thereof.

The single figure in the drawings herewith shows a section of my new and ornamental design of an endless wheel tire and which is made ornamental and attractive to the eye

by the butterfly development of the tread portion and the side panels and base in harmony therewith, so that an entirely new and original ornamental effect is obtained.

I claim:

The ornamental design for a wheel tire, as shown and described.

In testimony whereof I affix my signature in presence of two witnesses.

JAMES CHRISTY.

Witnesses:

E. M. FISHER,
F. C. MUSSUN.
